FOLDABLE RECLINING CHAIR

Knud Erik Andreas Schmidt, Copenhagen,
DenmarkApplication August 29, 1947, Serial No. 771,247
In Denmark September 3, 1946

1. Claim. (Cl. 155—139)

1 My invention relates to folding beach chairs, and relates particularly to a chair which in its extreme reclining position may be used as a cot.

Conventional reclining deck or beach chairs have been provided with backs which may be inclined at various angles. However, in the conventional chairs the canvas is supported longitudinally upon the seat and the back rest. Since the canvas when thus supported is prone to sag, the user is forced into a crouched position which is uncomfortable in both the upright and the reclining positions. Although comfortable upright chairs and comfortable folding cots are well known, a folding chair which is equally comfortable in the upright and the reclining positions has not, to my knowledge, hitherto been available.

It, therefore, is an object of my invention to provide a folding beach chair which may be used either as a chair or as a cot in comfort.

Another object of my invention is to provide a novel method of supporting the canvas for the seat and back, whereby there is little tendency for the canvas to loosen, and whereby the canvas may readily be replaced if necessary.

Another object of my invention is to provide a folding chair whose arm rests are automatically lowered when the chair is converted into a cot.

Other objects of my invention are to provide an improved device of the character described, that is easily and economically produced, which is sturdy in construction, and which is highly efficient in operation.

With the above and related objects in view, my invention consists in the details of construction and combination of parts, as will be more fully understood from the following description, when read in conjunction with the accompanying drawing in which:

Referring now to the drawings, wherein similar reference characters designate similar parts, I show in Figs. 1 to 7 a form of beach chair which can be converted into a cot. In Figs. 10 to 12, I show a second form of such a chair. In Figs. 13 and 14, I show a third form, and in Fig. 15, I show a fourth form of such a chair.

In the first form, illustrated in Figs. 1 to 7, the chair comprises a pair of sides and a seat, each side being designated generally as A. The back rest of the chair is formed by two side members, each designated as B. The sides A and B are hinged together as at 20, whereby the back rest and the seat may be inclined with respect to each other at various angles, or whereby they may be aligned end to end, as shown in Fig. 3 where the chair is used as a cot. Front legs, each desig-

nated as C, are pivoted to both seat side members A as at 22, and both legs are connected by transverse braces 24. A combination arm rest and rear leg, designated generally as D, is pivoted near its middle to each back rest member B as at 26, and both members D are connected by transverse braces 28. The arm rest ends of the members D are also pivoted to the upper ends of the front legs C, as at 30. It may be seen that the members A, B, C and D form a collapsible quadrilateral by virtue of the pivotal connections at 22, 26, 30 and the hinge 20. In order to maintain the inclination of the back rest with respect to the seat, at any one of several positions, adjustable braces E are provided. Braces E each have their lower ends pivoted to a member D, as at 32, and at their upper ends carry pins 34 which are adapted to nest in any of a series of cutouts 36 located along the rear edges of the back rest sides B. Accordingly, by inserting the adjustable brace pins 34 in the various cut-outs 36, the back rest becomes locked at the various degrees of inclination. As shown in Fig. 3, when the adjustable braces are engaged in the cutouts nearest the ends of the members B, the back rest becomes a horizontal continuation of the seat and my chair then becomes a cot.

In order to increase the leg room of the cot thus formed, I add a foot rest extension, consisting of side members 38 and 40, between which canvas is stretched, and a curved end brace 42, which conforms to the natural hollow curvature of the canvas when the cot is occupied. Legs 54 and 56 are pivoted to the sides 38 and 40 at points 57 and 58 and blocks 60 serve as stops.

In order to prevent the canvas K which is stretched laterally between the sides A and the sides B from loosening, I provide the cinching arrangement shown in Figs. 6 and 9. The sides A and B are each provided with a circular hollow 50 which extends along their inner edges. Each end of the canvas is rolled several times about a round bar or dowel 52, and the completed roll is placed in the circular hollow 50 and secured thereto, as by nails or screws 56. The latter fastenings may be removed in order to repair or replace the canvas.

In Figs. 10, 11, and 12, I show a second form of my invention. This chair consists of members F which serve as sides for the seat, and also as rear legs. The front legs G are pivoted at or near their midsections to the members F as at 62, and are also pivoted at their upper ends to the arm rests H, as at 64. Members J serve as sides for the back rest, and are hinged at their lower

ends to the midsection of the members F. The arm rests are pivotally connected to the back rest members J at an intermediate point 66. The upper length of the members J are provided with the cut-outs 36 previously described for the first form of my chair. Adjustable braces E have their lower ends pivoted to the members F, and their upper ends are provided with pins, which may be engaged with the various cut-outs desired, in the manner previously described, to obtain the various inclinations of the back rest.

In my first form of chair I show hinges 20 which may be any conventional strap hinges. For the second form of my chair, and also for the third and fourth forms, I prefer to use a special hinge shown in Fig. 9, which consists of two laterally-adjacent plates 58 and 59 and which are rotatably joined by a rivet 61. Each plate is screwed or otherwise fastened to the inner edge of the hinged chair members, such as F and J in this form of chair being described.

In the first and second forms of my convertible chair, the arm rests project above the cot level, succeeding forms of my chair are shown in which the arm rests lower to the approximate level of the cot.

In the third form of my convertible chair shown in Figs. 13 and 14, the back rest sides L are pivoted to end braces 71 as at 70, and are also hinged to the seat-and-leg side members M as at 72. Separate arm rests N are hinged to the back rest sides L at at 74, and also to arm rest braces P as at 76. The lower ends of the arm rest braces P are pivotally connected to the members M as at 78. The end braces 71 are also pivotally connected to the front legs Q as at points 83. Each stretcher bar R has one end pivotally connected at point 83, and its other end pivotally connected near the ground end of one of the members M, as at 82. The upper ends of the front legs Q are pivotally connected near the front ends of the members M, as at 80. The adjustable braces E and the cut-outs 36 are used to provide various inclinations of the back rest as previously described. As shown in Fig. 14, this form of my chair folds when used as a cot in such manner that the arm rests N lower substantially to the level of the cot. The difference in levels is purposely exaggerated in the figure so that the manner in which the parts fold may be shown.

In the fourth form of my invention, the seat side members S are pivotally supported by the front legs T near one end as at points 90, and the other ends of the members S are hinged to the sides V of the back rest. Members W, which serve both as arm rests and also as rear legs, each is pivotally connected to one back rest member V as at 92, and also at the front ends the members W are pivotally connected to levers X which are pivoted to the seat members S at points 94.

The lower ends of the levers X are pivotally connected to points 96 on the front legs T by means of links Y. Adjustable back rest braces E co-operate with cut-outs 36 in the back rest members V as was previously described, so as to provide the desired inclination of the back rest. When this particular chair is converted into a cot, as by engaging the back rest braces E in the most extreme cut-out 36, the arm rest ends of the members W lower to the level of the cot.

The canvas which forms the seat and the back rest is attached in all of the forms of my invention in the same manner. It can be seen that the canvas is protected against chafing by the adjacent side members when the chair is being folded, or converted.

Although my invention has been described in considerable detail, such description is intended as being illustrative rather than limiting, since the invention may be variously embodied, and the scope of the invention is to be determined as claimed.

I claim as my invention:

An adjustable back folding chair convertible to a cot, consisting of two identical side frames, each frame arranged in a vertical plane parallel to the other frame, said frames being maintained at a suitable distance from each other by means of horizontal transverse bars; said frames comprising a combination rear leg and arm rest pivotally connected to a back rest side member and to a front leg, a seat side member pivotally connected to said back rest side member and to said front leg, and canvas or other fabric suspended upon said transverse bars laterally between the seat and back rest side members of each frame to form a support for the occupant of the chair, a plurality of cut-outs located in the rearmost surface of said back rest side member, a brace pivotally connected to said combination rear leg and arm rest, and adapted to engage any one of said cut-outs, whereby said back rest may be inclined at various angles of elevation with respect to the ground.

KNUD ERIK ANDREAS SCHMIDT.
